US00D987372S

(12) **United States Design Patent** (10) **Patent No.:** **US D987,372 S**
(45) **Date of Patent:** **** May 30, 2023**

(54) **POURING SHIELD**

- (71) Applicant: **WHIRLPOOL CORPORATION**, Benton Harbor, MI (US)
- (72) Inventors: **Timothy Eric Heater**, Hartford, MI (US); **Naveen Jayabalan**, Stevensville, MI (US); **John W. McConnell**, St. Joseph, MI (US); **Brandon Tyler Mock**, Chicago, IL (US); **Nicholas Hill Schutte**, St. Joseph, MI (US); **Rohit Ranjan Singh**, Pune (IN)
- (73) Assignee: **Whirlpool Corporation**, Benton Harbor, MI (US)

(**) Term: **15 Years**

(21) Appl. No.: **29/739,119**

(22) Filed: **Jun. 23, 2020**

(51) LOC (14) Cl. **31-00**

(57) **CLAIM**

The ornamental design for pouring shield, as shown.

DESCRIPTION

FIG. 1 is a first top perspective view of a pouring shield of the present disclosure;

FIG. 2 is a second top perspective view of the pouring shield of FIG. 1;

FIG. 3 is a first bottom perspective view of the pouring shield of FIG. 1;

FIG. 4 is a second bottom perspective view of the pouring shield of FIG. 1;

FIG. 5 is a first side elevational view of the pouring shield of FIG. 1;

FIG. 6 is a second side elevational view of the pouring shield of FIG. 1;

FIG. 7 is a third side elevational view of the pouring shield of FIG. 1;

FIG. 8 is a fourth side elevational view of the pouring shield of FIG. 1;

FIG. 9 is a top plan view of a pouring shield of the present disclosure; and,

FIG. 10 is a bottom plan view of a pouring shield of the present disclosure.

The broken lines depict portions of the article that form no part of the claimed design.

1 Claim, 5 Drawing Sheets
